LINING WEAR GAUGE FOR DISC AND DRUM BRAKES

Robert Turner Paulk, South Bend, Ind., assignor to The
Bendix Corporation, South Bend, Ind.

Filed Feb. 22, 1972, Ser. No. 228,471

Term of patent 14 years

Int. Cl. D10—04

U.S. Cl. D52—6 R

FIG. 1

FIG. 2

FIG. 3

FIG. 1 is a front perspective view of a lining wear gauge for disc and drum brakes showing my new design;

FIG. 2 is a top plan view thereof;

FIG. 3 is a side elevational view thereof.

I claim:

The ornamental design for a lining wear gauge for disc and drum brakes, as shown.
